UNITED STATES PATENT OFFICE.

HERBERT G. BEEDE, OF PAWTUCKET, RHODE ISLAND.

DESIGN FOR A GUIDE-WIRE FOR THREAD-TWISTING MACHINES.

SPECIFICATION forming part of Design No. 33,029, dated July 31, 1900.

Application filed June 14, 1900. Serial No. 20,374. Term of patent 14 years.

To all whom it may concern:

Be it known that I, HERBERT G. BEEDE, a citizen of the United States, residing at Pawtucket, in the county of Providence and State 5 of Rhode Island, have invented and produced a new and original Design for a Guide-Wire for Thread-Twisting Machines, of which the following is a specification, reference being had to the accompanying drawing, forming a

part thereof.

My invention relates to a guide-wire, and particularly to a thread-guide wire for twisting-machines or twisters for twisting thread; and it consists in a new and original design 15 for a guide-wire, as will be hereinafter fully described.

The drawing is a side view of a guide-wire, showing my design.

My design for a guide-wire consists of a straight or vertical portion *a*, loop *b* at its 20 lower end, straight portion *c*, and a projecting end *d*, extending at substantially right angles to the portion *c*. At the upper end of the straight portion *a* is the eye *e*, with the free end *f* extending at substantially right angles to the straight portion *a* and with a screw-thread on the end thereof. 25

What I claim is—

The design for a guide-wire for thread-twisting machines, substantially as shown 30 and described.

HERBERT G. BEEDE.
